CLEMENT W. KELL, OF RIDLEY PARK, PENNSYLVANIA, AND WILLIAM O. ASHE, OF ST. LOUIS, MISSOURI, ASSIGNEES TO GENERAL STEEL CASTINGS CORPORATION, OF GRANITE CITY, ILLINOIS, A CORPORATION OF DELAWARE

LOCOMOTIVE STRUCTURE

Application filed June 18, 1931. Serial No. 545,318.

This invention relates to railway rolling stock and consists in novel construction of a locomotive underframe and particularly the air brake cylinders and other associated equipment located near the front of the underframe.

In present locomotive construction, it is customary to secure the main air brake cylinders to transverse members of the underframe or to convenient brackets thereon by means of bolts engaging suitable flanges on the cylinders and the members or brackets. These securing and mounting elements must withstand large stresses due to continual application of the brakes and these stresses increase with the size of the locomotive.

The main object of the present invention is to strengthen the air brake cylinders and their attachment to the underframe, as well as surrounding portions of the locomotive bed by providing a rigid transverse member which will include in an integral structure the brake cylinders as well as various brackets for attaching locomotive equipment.

Another object of the invention is to locate the air brake cylinders and an adjoining expansion plate bracket in such position that they will serve as a transverse tie between locomotive side frames.

These objects and others appearing hereafter are attained in the structures illustrated in the accompanying drawings in which—

Figure 1 is a top view of a portion of a locomotive bed embodying one form of the invention.

Figure 2 is a side view of the same.

Figures 3, 4, and 5 are vertical sections taken on the corresponding section lines of Figure 1.

Figure 6 is a vertical transverse section taken on the line 6—6 of Figure 1.

Figure 7 is a view corresponding to Figure 6, but illustrating a modified form of the invention.

Figure 8 is a top view of a portion of a locomotive underframe embodying another modification.

Figure 9 is a side view of the same.

Figure 10 is a vertical transverse section, 50 the left half of which is taken on the line

10—10 of Figure 9 and the right half of which is taken on the line 10a—10a of Figure 9.

Figure 11 is a detail vertical longitudinal section taken on the line 11—11 of Figure 8. 55

Figure 12 is a detail longitudinal horizontal half section taken on the line 12—12 of Figure 9.

In Figures 1 and 2 the invention is illustrated as applied to an integral locomotive bed including box section side frame 1, having pedestals 2 formed therein, connected by substantially flat transverse bottom and top webs 3 and 4 which are perforated to facilitate casting and to decrease the weight 60 of the structure. Mounted on ribs 4a extending across the depressed top web 4 of the bed near the rear ends of the cross head guides 5, is a transverse member 6 substantially of box section, as shown in Figure 5. The member 6 projects outwardly from each side of the bed and has flat vertical portions 7 at each end forming brackets for attachment of yokes 8 for mounting the cross head guides 5. 75

The body walls of air brake cylinders 9 and 10 extend transversely through member 6 above the depressed top web 4 and are integral with the web and ribs. Cylinders 9 and 10 merge with the bottom web 6a of member 6 80 and occupy a substantial portion of the hollow interior of the member. For the purpose of illustration, cylinder 9 is shown with pressure head 11 integral and non-pressure head 12 secured to the body of the cylinder by 85 the usual bolting flanges. Cylinder 10 has non-pressure head 13 integral therewith and pressure head 14 secured to the body of the cylinder. It will be understood, however, that in practice the cylinders will preferably 90 be made uniform.

Where the pressure ends of the cylinders are left open, transverse member 6 and cylinders 9 and 10 are spaced a sufficient distance 95 rearwardly of the boiler supporting saddle 15 to permit the application of a machine 16 for boring the cylinders from the front.

The driver brake rods on each side of the locomotive are operated in the usual manner by pistons 17 operating in the cylinders 9 and 100

10 and brake levers 18, which are pivoted to fulcrums 19 formed integral with the bed. The structure shown in Figure 7 corresponds with the form previously described, 5 except that yoke 20, mounting cross head guides 21 is formed integral with bracket 22 projecting sidewardly from the end of transverse member 23. Air brake cylinders 24 are integral with member 23 as in Figures 10 1 to 6.

Figures 8 to 12 illustrate a modified structure in which the transverse tie between the side frames 27 is a separately formed member adapted to rest upon and be secured to the 15 side frames and to brace them transversely of the underframe and includes vertically disposed air brake cylinders 25, an expansion plate bracket 26, brake hanger brackets 35, and brake lever fulcrum brackets 38 as integral parts of the member.

The body of the member includes rectangular frames 36 adapted to engage the locomotive side frames 27 and to be secured thereto by bolts or rivets passing through openings 37. Integral brackets 38 project from the lower portions of frames 36 to mount the fulcrum 51 for the brake levers 41. These frames 36 are connected by horizontal transverse webs 28 and 31 arranged at different 20 levels and reinforced by a depending inverted T section 29 and the expansion plate bracket 26, respectively. The lower portions of frames 36 are connected by an angular tie 42, there being a central opening 43 above the tie 25 to lighten the casting.

The lower ends 39 of the brake cylinders 25 merge with the web 28 and the flange 50 of reinforcing member 29 merges with the lower end of the non-pressure head of the 30 brake cylinder. Diagonal ribs 34 brace the expansion sheet bracket 26. The device includes shoulders 30 for resting on the locomotive side frames 27. The upper ends of the brake cylinders are open to permit the 35 insertion of a boring or reaming tool and the insertion of pistons and the cylinder pressure heads (not shown) are applied after assembly.

The rectangular frames 36 are provided 40 with recesses 44 to accommodate the spring hangers 45 which connect the springs 46 with the equalizers 47.

Each of the structures comprises a rigid, durable transverse member in which various 45 elements, usually secured to the locomotive bed by bolts or rivets, are united in an integral structure, thus eliminating the weight and bulkiness of the usual bolting flanges and at the same time utilizing the metal walls 50 of the various elements to increase the strength of the underframe.

Obviously, the invention is not limited to the exact structures shown, and details such as the contour of various parts as well as the 55 formation of various brackets, etc., integral

with the casting may be modified within the spirit of the invention. Moreover, any of the novel transverse structures shown could be either formed integral with the remainder of the locomotive bed or secured thereto in the usual manner of constructing built up underframes. We claim the exclusive use of these and other variations such as come within the scope of our claims.

We claim:

1. In a locomotive underframe, side frames, a boiler supporting saddle, and an integral structure comprising a transverse member spaced substantially from said saddle and applied to and extending between said side frames and outwardly beyond the same, and including a brake cylinder.

2. In a locomotive underframe, side frames and an integral structure comprising a transverse member applied to and extending between said side frames and outwardly beyond the same, and including a cross head guide yoke bracket on the end of said member, and also including a brake cylinder.

3. In a locomotive underframe including side members, an integral structure comprising a box section cross tie extending between said side members, and an air brake cylinder with its wall merging with the bottom web of said cross tie and extending between the upper walls thereof.

4. In a locomotive underframe including spaced side members, an integral structure comprising a box section cross tie extending between said side frames and outwardly beyond the same, and an air brake cylinder positioned within the interior of said cross tie, there being an upright portion on an end of said member for mounting a cross head guide yoke.

5. In a locomotive underframe, spaced side members, and a substantially horizontal web extending between said side members and having a depressed portion, and an integral structure including upright ribs extending transversely across said depressed portion, an elongated box shaped member on said ribs, and an air brake cylinder within said member.

6. In a locomotive underframe, spaced side members, and an integral structure including a substantially horizontal web extending between said members, upright ribs traversing said web, an elongated box section cross member on said ribs, an air brake cylinder located within the interior of said cross member, and a cross head guide yoke bracket on the end of said cross member.

7. A cross tie for a locomotive underframe including in an integral structure a substantially horizontal web having portions for resting on underframe side members, and a pair of air brake cylinders merging with said web and with each other and co-operating to

form a rigid brace extending substantially from side to side of the underframe.

8. A cross tie for a locomotive underframe including in an integral structure, a box section member having portions resting on side members of the underframe, and a pair of air brake cylinders within the interior of said member and merging at the middle to form a rigid brace extending substantially from side to side of the underframe.

9. A cross tie for a locomotive underframe comprising an integral structure including an air brake cylinder and a boiler expansion plate support bracket spaced therefrom, and rectangular frames for attachment to the side members of the locomotive underframe.

10. A cross tie for a locomotive underframe comprising an integral structure including a substantially horizontal web, an air brake cylinder on said web, a pair of attaching members depending from said web for engaging opposite side frames on the bed, and a brake lever fulcrum bearing in each of said members.

11. A cross tie for a locomotive underframe comprising an integral structure including a substantially horizontal web, a pair of air brake cylinders and a boiler expansion plate bracket on said web, and a brake hanger bracket at the end of said first mentioned bracket.

12. A cross tie for a locomotive underframe comprising an integral structure including a substantially horizontal web, said web having portions at different levels, an air brake cylinder on one of said portions, and a boiler expansion plate bracket on the other of said portions.

13. A cross tie for a locomotive underframe comprising an integral structure including a plurality of substantially horizontal transverse elements at different levels, the lower of said elements resting on the underframe side members and the upper of said elements having depending flanges resting on said members, an air brake cylinder on said higher element, and a boiler expansion plate bracket on said lower element.

14. A cross tie for a locomotive underframe comprising an integral structure including a plurality of substantially horizontal transverse elements at different levels, the lower of said elements resting on the underframe side members and a portion of said upper element having flanges at each side for resting on the underframe side members and another portion thereof being recessed to permit the passage of a spring hanger between said portion and the side member, and an air brake cylinder on said upper portion and a boiler expansion plate bracket on said lower portion.

15. A cross tie for a locomotive underframe comprising an integral structure including upright frames for attachment to under-

frame side members, a transverse I-shaped structure, and a substantially horizontal web extending between the tops of said member, an air brake cylinder on the top web of said I-shaped structure, and a boiler expansion plate bracket on said web.

16. In combination in a locomotive underframe, spaced side members and a transverse brace for said members including an air brake cylinder and a boiler expansion plate bracket.

17. In combination in a locomotive underframe, spaced side members, and a transverse brace for said members and including a substantially horizontal web, attaching elements depending from each side thereof, and an air brake cylinder and a boiler expansion plate bracket on said web.

In testimony whereof we hereunto affix our signatures this 8th day of June, 1931, and 27th day of May, 1931, respectively.

CLEMENT W. KELL.
